UNITED STATES PATENT OFFICE.

JOSEPH J. WEINANDT, OF AYR, NORTH DAKOTA.

FIRE-ESCAPE.

1,242,286.

Specification of Letters Patent.

Patented Oct. 9, 1917.

Application filed May 5, 1916. Serial No. 95,541.

To all whom it may concern:

Be it known that I, JOSEPH J. WEINANDT, a citizen of the United States, residing at Ayr, in the county of Cass, State of North Dakota, have invented a new and useful Fire-Escape; and I do hereby declare the following to be a full, clear, and exact description of the invention, such as will enable others skilled in the art to which it 10 appertains to make and use the same.

The present invention relates to certain new and useful improvements in fire escapes, and has for its object to provide a device of this character which embodies 15 novel features of construction whereby it can be compactly folded so as to be conveniently carried in a trunk or suitcase, and which can be quickly brought into operative position should the necessity arise.

20 Further objects of the invention are to provide a portable individual fire escape which is comparatively simple and inexpensive in its construction, which can be quickly fitted to any window and used upon tall as 25 well as low buildings, which admits of the person regulating his speed of descent as desired, and which by being subsequently drawn up and used again will provide for the escape of a number of persons.

30 With these and other objects in view, the invention consists in certain novel combinations and arrangements of the parts as will more fully appear as the description proceeds, the novel features thereof being 35 pointed out in the appended claims.

For a full understanding of the invention, reference is to be had to the following description and accompanying drawing, in which:—

40 Figure 1 is a front elevation of a portion of a building and a window therein, showing the manner of applying a fire escape constructed in accordance with the invention to the window, portions of the 45 fire escape slide being shown in section to more clearly illustrate the details thereof.

Fig. 2 is a transverse sectional view through the window frame shown by Fig. 1, the fire escape being shown in side elevation.

Fig. 3 is a horizontal sectional view through the window frame, the collapsible bar which engages the inner face of the window frame appearing in top plan view, and portions thereof being broken away and 55 shown in section.

Fig. 4 is an enlarged longitudinal sectional view through the slide and rope gripping means.

Fig. 5 is an enlarged detail sectional view 60 through one of the rope guides which are applied to the rungs of the ladder.

Corresponding and like parts are referred to in the following description and indicated in all the views of the drawings by 65 the same reference characters.

Specifically describing the present embodiment of the invention, the numeral 1 designates the window frame of a building, to which the fire escape is shown as applied. 70 A collapsible bar is adapted to extend transversely across the window and to engage the sides of the window frame 1 on the inside of the building, said bar being shown in the present instance as comprising the telescoping sections 2 and 3 which can be locked in an adjusted position by means of the set screw 4. The window frame engaging bar can thus be readily collapsed and packed in a trunk or suitcase, 75 although the construction is such that it can be very quickly fitted to the window frame and locked in operative position. The outer end of the telescoping section 2 is provided with a short lateral arm 5 which 80 fits around and engages an inside edge of the window frame so as to hold the bar against longitudinal movement in one direction. An eye or ring 6 projects from the section 2 and has the cable 7 connected 85 thereto, said eye being slightly spaced from the end of the section 2 so as to be disposed close to one side of the window frame when the transverse bar is in operative position, thereby reducing the strain upon the transverse bar and rendering it unnecessary to make the bar excessively heavy. The opposite telescoping section 3 is provided at the extremity thereof with a prong 8 which 90 is adapted to bite into the other side of the 95 window frame. The cable 7 is connected to the eye 6 and passes around the outer end of the section 2 and then through the eye 9 of the section 3, the cable 100 being secured to the outer end of the section 3.

window frame to assist in holding the transverse bar in position. At a point suitably spaced from the end thereof the section 3 is provided with a lateral lug 9, which projects into the opening of the window frame at a point adjacent the side thereof which is engaged by the prong 8.

The carriage which is arranged to travel upon the cable 7 for the purpose of conveying an occupant of the building safely to the ground in case of fire, includes a slide 10 through which the cable 7 is threaded, and a rope ladder L pendent from the slide, and arranged to be directed in its movements by the cable. The flexible side ropes 11 of the ladder L preferably converge toward the top thereof, where they are permanently secured to laterally projecting arms 12 at the base of the slide. The rungs 13 of the rope ladder are permanently connected at the ends thereof to the side ropes 11, the middle portions of the rungs having clips 15 applied thereto, and the clips carrying guide eyes 15^a through which the cable 7 is threaded. While descending the person is supposed to stand upon the lowermost rung 13 and grasp the slide 10 in his hands, said slide being provided with a brake mechanism which engages the cable 7 to regulate the speed of the descent.

Arranged upon one side of the passage through the slide 10 is a pair of vertically aligned and slightly spaced rollers 16. A third roller 17 is arranged upon the opposite side of the cable 7 and journaled upon a brake lever 18, in such a manner that it can be forcibly thrust into the space between the two rollers 16 for co-operation therewith to grip the cable 7 and either lock the slide 10 in a fixed position upon the cable, or regulate the descent of the carriage upon the cable. The lower end of the brake lever 18 is pivoted at 19 to one side of the slide 10, while the upper end thereof is curved inwardly to conform to the contour of the upper end of the slide 10, and arranged to be pressed inwardly by a hand grasping the upper end of the slide. This upper end of the slide is preferably tapered, and a swinging bail 20 is pivotally mounted theron so that it can be swung around the upper end of the brake lever 18. A thumb screw 21 is threaded in the swinging end of the bail 20 and by tightening this thumb screw 21 the brake lever 18 can be forced inwardly and the rollers caused to tightly grip the cable 7 to lock the slide against movement upon the cable. It will also be obvious that by tightening and loosening the thumb screw 21 the speed of descent can be regulated as desired, and there is no danger of the carriage getting beyond the control of the operator, since the thumb nut prevents the cable from being suddenly released.

Projecting rearwardly from the slide 10 is a runner 22 which is adapted to engage the face of the building in such a manner as to hold the slide spaced therefrom and prevent the operator from skinning or injuring his hands. This runner 22 is preferably formed with an outer edge which is inclined upwardly and away from the slide, so that the device will slip freely over any ledges or projections upon the building. The lowermost rung 13 of the rope ladder L is provided at its extremities with clips 23, said clips carrying inwardly extending arms 24 upon which the rollers 25 are journaled. These rollers are adapted to engage and travel upon the face of the building and serve to hold the lower end of the ladder properly spaced from the building. It will thus be seen that the runner 22 and rollers 25 cooperate with each other to hold the carriage away from the building so that the hands and feet of the operator will not be bruised or skinned by contact with the building.

In the operation of the device, the window frame engaging bar is first adjusted to the proper length and then fitted to the inside of the window frame, the eye 6 and lateral arm 5 embracing one side of the window frame, while the prong 8 penetrates the opposite side thereof, the lateral lug 9 projecting into the window opening adjacent to the said opposite side thereof. The slide 10 is then positively locked upon the cable 7 by tightening the thumb screw 21, and the carriage and cable dropped through the window, the rope ladder L being properly threaded upon the cable 7 and pendent from the slide 10. The operator will now crawl through the window, place his feet upon the upper rungs of the rope ladder 11, and then descend the rope ladder to the lowermost rung thereof, in which position he can conveniently grasp the slide 10 and manipulate the thumb screw 21. The brake mechanism may now be loosened by slightly unscrewing the thumb screw 21, and the descent of the carriage, together with its passenger, regulated as desired by manipulating the thumb screw. After the descent has been completed, and the passenger discharged, the carriage can be drawn up to the window and used for the descent of another person, thereby enabling a number of persons to escape from the building in succession, if necessary.

Having thus described the invention, what I claim as new and desire to secure by Letters Patent, is:

A collapsible fire escape including a cable, a tubular slide mounted upon the cable and provided at its lower end with laterally extending arms, brake means upon the tubular slide for engagement with the cable, flexible

side ropes pendent from the lateral arms of the tubular slide on opposite sides of the cable, rungs connecting the side ropes and coöperating therewith to provide a collapsible ladder construction, and independent guide members projecting from intermediate portions of the several rungs for engagement with the main cable.

Copies of this patent may be obtained for five cents each, by addressing the "Commissioner of Patents, Washington, D. C."

In testimony whereof I have signed my name to this specification in the presence 10 of two subscribing witnesses.

JOSEPH J. WEINANDT.
